PRINTING PLATE MOUNTING

William F. Brügmann, Evanston, Ill.

Application October 27, 1933, Serial No. 695,443

34 Claims. (Cl. 101—388)

This invention relates to improvements in printing plate mountings of the type in which the plate holders are mounted to move in grooves in the base or support, the holders being first 5 adjusted into close proximity to the edge of the plate and then given an additional or final adjustment to grip and hold the plate in position.

The mounting of printing plates in connection with both flat bed and rotary printing presses 10 has always presented a difficult proposition. Plate control means for holding and registering such printing plates have in later years, and in the more advanced devices, taken the form of diagonal grooves, in which grooves steel racks 15 have been inserted, and the various printers plate clamps have been designed to operate in the racks in these grooves for the micromatic control of such printing plates.

In the case of rotary printing presses racks 20 have been permanently fastened in the diagonal grooves by means of pins, and where pins are used as the rack securing means, the rack material must necessarily be soft enough for drilling so as to permit insertion of the fastening 25 pin.

Another great objection in the present methods lies in the difficulty of repairs in case of mechanical injury to the teeth of the racks. When such injury occurs, it is, in some cases, 30 necessary to remove the cylinders from the press, remove the bearing rings, remove the fastening means and then drive or pull out the injured racks, replacing them with new racks.

It is also sometimes necessary to drill out the 35 pins in order to remove the racks, which is a difficult and tedious job.

To overcome some of these difficulties and objections there is provided improved means for removably securing the racks in position which 40 allows—first, the use of a hardened rack, giving greater strength and more wear resistance. Second—a rack retaining means which permits easy and convenient repairing without the necessity of drilling out holding pins, removing cylinders 45 and bearers to effect repairs, or the removal of the entire rack from the groove.

To the attainment of these ends and the accomplishment of other new and useful objects as will appear, the invention consists in the features 50 of novelty in substantially the construction, combination and arrangement of the several parts hereinafter more fully described and claimed and shown in the accompanying drawing illustrating this invention, and in which

55 Figure 1 is a top plan view of a portion of a

printing plate base and mounting, partly in elevation, partly broken away and partly in section, constructed in accordance with the principles of this invention.

Figure 2 is an end elevation of Figure 1. 5

Figure 3 is a transverse vertical sectional view, on an enlarged scale, of one form of fastening means for the rack and showing the racks in position in the groove.

Figure 4 is a perspective view of one form 10 of fastening means.

Figure 5 is a view similar to Figure 3, on a different scale, of another form of the invention.

Figure 6 is a view similar to Figure 5, of still 15 another form of the invention.

Figure 7 is a detail perspective view of the fastening means shown in Figure 6.

Referring more particularly to the drawing the numeral 16 designates generally a base or mounting provided with grooves 11 opening through the 20 face thereof and extending diagonally thereacross. These grooves are of any desired size and configuration and provided in the opposite upright walls of the groove are recesses 12 extending for the entire length of the groove and 25 through the ends of the wall.

These grooves 12 are spaced below the face of the plate and above the bottom 13 of the groove, and are of a size and configuration to receive rack 30 members 14. A portion of the rack members 14 project into the groove 11 and are provided with teeth 15 which are adapted to be engaged by the advancing means of the register hook which cooperates with the base or mounting, and a portion of which moves within the groove 11. 35

These racks 14 are removably held in position in any desired or suitable manner. A simple and efficient means is disclosed in Figures 3, 4 and 5, and consists essentially of a substantially U shaped member 16 constructed of any suitable 40 resilient material having an inherent tendency to cause the longitudinal edges of the element to separate.

In the form of the invention shown in Figure 3, the element 16 is seated in the groove 11 preferably to rest upon the bottom thereof and the edges 17 project into recesses 18 in the lower face of the portion of the rack members 14 which project into the groove 11 so that after the racks 14 are placed in position in the recesses 12, the 50 edges 17 of the member 16 may be pressed towards each other so as to allow the fastening element 16 to be inserted in the groove 11 between the toothed edges of the rack members 14 and beneath the projecting portions of the rack mem- 55

bers. When in this position and when the member 16 is released its inherent resiliency will cause the edges 17 to separate and they will then enter the recesses 18 in the lower faces of the rack members 14 and frictionally hold them in position.

If desired and in order to prevent the fastening members 16 from moving longitudinally in the groove 11, any suitable anchoring means may be provided, such for instance as a center punch prick 19 to engage the bottom 13 of the groove 11.

In the form of the invention shown in Figure 5, the rack members 20 are of a substantially inverted L shaped configuration, the body portion 15 of the rack members being seated in recesses 21 opening through the side walls of the groove 11. The face 22 of the rack member projects beyond the side walls of the groove so as to form a shoulder with the tooth carrying portion 23. In this 20 form of the invention the securing element 16 when placed in position, will rest upon the bottom 13 of the groove and the edges 17 will engage the shoulder of the rack members 20 and will project under the overhanging tooth carrying portion of 25 the rack members.

Thus it will be seen that the rack members will be frictionally but removably held in position.

In the form of the invention shown in Figures 6 and 7 the securing member comprises a body portion 30 24 provided with upwardly projecting spring arms 25, the upper extremities of these arms being preferably rounded or cut away as at 26.

In inserting this form of fastening means the arms 25 are pressed towards each other and the 35 fastening member is placed into the groove 11, so that they will extend in general directions lengthwise of the groove. The arms 25 are of such a length that when the body portion 24 rests upon the base 13 of the groove 11, the upper extremities of the arms will be below the portions 40 of the rack members 20 which carry the teeth 23 and which overhang the groove 11. The fastening member is then axially rotated so that the arms 25 will extend transversely of the groove 11, and when the arms are released their inherent 45 resiliency will cause them to separate, resulting in the upper extremities of the arms passing beneath the shoulders 27 formed by the overhanging portion of the rack.

The fastening member 24 may be axially rotated in any suitable manner, but a simple and efficient means for accomplishing this result comprises an opening 28 in the bottom or body of the fastening member, which is angular in cross section, and which is adapted to receive a suitable 55 tool or implement for accomplishing the rotary movement both into and out of locking position. In this form of the invention and when it is desired to remove the fastening means, it is only necessary to axially rotate the same until the extremities of the arm 25 pass from beneath the shoulders 27.

In the forms of the invention shown in Figures 3 and 5, the fastening members 16 may be removed by pressing the edges 17 towards each other in any suitable manner.

After these fastening devices have been removed it will be manifest that the rack section may be readily removed. The rack members are 70 preferably made in sections arranged end to end and one or more of the fastening members may be provided for each rack section, according to the length of the fastening members and of the rack sections.

75 The rack sections are set into the walls of the

grooves and arranged end to end, and the fastening members are spaced in the grooves, one or more for each rack section.

Each of the fastening members secures opposed 5 rack sections in position when a rack member is arranged along each side of the groove. However, should the rack member be arranged along one side of the groove only, then each of the fastening members will co-operate with the opposite wall of the groove to hold the rack section 10 in position.

Should a rack section break or be otherwise injured, necessitating repair, the fastening members are moved lengthwise of the grooves and beneath an adjacent rack section until the injured 15 rack section is free. The injured rack section may then be removed, through the top of the groove, if desired, and a new rack bar inserted. The fastening member which has been displaced to permit removal of the rack section may then be 20 moved back into normal position, and the rack member which has been inserted will be locked against displacement.

The upstruck portion 19 on the fastening member 16 will operate to hold the fastening member 25 against creeping longitudinally of the groove, but when it is desired to shift the fastening member lengthwise of the groove, the portion 19 will yield to permit such movement.

The operation of the form of the invention 30 shown in Figures 6 and 7 is the same as that described in connection with the form shown in Figures 3 and 5, but in this form of the invention, the fastening members are placed into locking and unlocking position by axially rotating the 35 same so as to cause the end of the arms 25 to pass out from beneath the shoulders or overhanging portions of the rack members. When the fastening member 24 has been rotated to the dotted line 40 position shown in Figure 6, it may be moved longitudinally in the groove or may be entirely removed, if desired.

Any suitable means (not shown) may be provided for preventing the rack members from creeping longitudinally in the grooves, if it is 45 found necessary to provide means in addition to the friction or stress created by the resiliency of the fastening elements 16 and 24.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. A printing plate base having a groove therein, sectional rack members in the side walls of the groove, said members spaced a substantial distance above the bottom of the groove, and means securing the sections in position and for free and independent removal from the groove, said means contacting the groove bottom and a face of the rack section, said rack members being supported in the groove independently of said securing means.

2. A printing plate base having a groove therein, sectional rack members in the side walls of the groove and arranged end to end, said members spaced a substantial distance above the bottom 70 of the groove, and means disposed within the groove individual to and between opposite rack section members for securing them in position for free removal from the groove, said means contacting the groove bottom and an adjacent face of 75

the rack, and said rack members being supported in the groove independently of said securing means.

3. A printing plate base having a groove therein, rack members in the side walls of the groove, and spring elements disposed between the rack members and within the groove for removably securing said members in position.

4. A printing plate base having a groove therein, rack members in the side walls of the groove, means securing the rack members in position and for free removal from the groove, and means entirely within the groove for maintaining the first said means against movement longitudinally of the groove.

5. A printing plate base having a groove therein, rack members in the side walls of the groove, means securing the rack members in position and for free removal from the groove, and means yieldingly anchoring the first said means against movement longitudinally of the groove.

6. A printing plate base having a groove therein, rack members set into the side walls of the groove and spaced a substantial distance above the bottom of the groove, a portion of said members overhanging and projecting beyond the side walls of the groove, and means within the groove and engaging said projecting portion and exerting only a lateral stress upon the rack members, for securing them in position and for free removal of the rack members, said rack members being maintained in position in the groove independently of said securing means.

7. A printing plate base having a groove therein, rack members set into the side walls of the groove, a portion of said members overhanging the groove, and spaced a substantial distance above the bottom of the groove, and means within the groove engaging said overhanging portion and exerting a lateral stress on said rack members for securing them in position and for free removal of the rack members through the top of the groove, said rack members being maintained in position independently of the securing means.

45 8. A printing plate base having a groove therein, sectional rack members set into the side walls of the groove a substantial distance above the bottom of the groove, and means exerting only a lateral stress upon said sections for removably securing them in position independently of each other, whereby one or more sections may be removed while the remaining sections remain intact in the groove, said rack members being maintained in position entirely independently of the said securing means.

9. A printing plate base having a groove therein, sectional rack members set into the side walls of the groove a substantial distance above the bottom of the groove and arranged end to end, and means for removably securing the sections of the rack members in position comprising locking members movable longitudinally of the groove out of engagement with a predetermined rack section to permit the latter to be removed while the securing means remains in the groove, said locking members exerting only a lateral stress upon said rack members.

10. A printing plate base having a groove therein, sectional rack members set into the side walls of the groove, and means for removably securing the sections of the rack members in position comprising locking members movable longitudinally of the groove out of engagement with a predetermined rack section to permit the latter to be removed while the remaining rack

sections remain intact and the securing means remains in the groove, said locking members exerting only a lateral stress on said rack members.

11. A printing plate base having a groove therein, rack members formed of sections arranged end to end and set into the side walls of the groove, and securing members within the grooves and arranged between opposed rack sections for removably securing them in position, said securing members exerting only a lateral stress on said rack members and being movable longitudinally of the grooves out of engagement with predetermined rack sections to permit the latter to be freely removed from the groove.

12. A printing plate base having a groove therein, rack members formed of sections arranged end to end and set into the side walls of the groove a substantial distance above the bottom of the groove, and securing members within the grooves and arranged between opposed rack sections for removably securing them in position, said securing members exerting only a lateral stress on said rack members and being movable longitudinally of the grooves out of engagement with predetermined rack sections to permit the latter to be freely removed from the groove and through the top thereof while the remaining rack sections remain intact in the groove.

13. A printing plate base having a groove therein, rack members formed of sections arranged end to end and set into the side walls of the groove, and securing members within the grooves and arranged between opposed rack sections for removably securing them in position, said securing members exerting only a lateral stress on said rack members and being individual to the sections and movable longitudinally of the grooves out of engagement with predetermined rack sections, to permit the latter to be freely removed from the groove and through the top thereof while the remaining rack sections remain intact and the securing member remains in the groove.

14. A printing plate base having a groove therein, rack sections set into the wall of the groove for free removal therefrom and arranged end to end, and fastening members for the rack sections, said fastening members providing a structure adapted to be placed under tension and inserted into the groove and to expand when positioned in the groove for holding the rack sections in position.

15. A printing plate base having a groove therein, rack sections set into the wall of the groove for free removal therefrom and arranged end to end, and fastening members for the rack sections, said fastening members providing a structure adapted to be placed under tension and inserted into the groove and to expand when positioned in the groove for holding the rack sections in position said fastening members adapted to be moved lengthwise of the groove out of securing position with its rack section to permit the latter to be freely removed from the groove.

16. A printing plate base having a groove therein, a rack recessed into the wall of the groove, the bottom of the recess being spaced for a substantial distance above the bottom of the groove, and fastening means for removably securing the rack in position, said fastening means providing a structure positioned within the groove and embodying means operating to exert a lateral pressure only upon the rack, and adapted for displacement upon the groove bottom with respect to the rack to release the latter and re-

- maining in the groove while the rack is removed from the groove.
17. A printing plate base having a groove therein, a rack set into the wall of the groove a substantial distance above the bottom of the groove, and fastening means for removably securing the rack in position, said rack being supported independently of the fastening means, and said fastening means providing a structure arranged entirely within the groove and removably engaging the rack, and exerting only a lateral stress upon the rack.
18. A printing plate base having a groove therein, a rack set into the wall of the groove, and fastening means for removably securing the rack in position, said rack being supported independently of said fastening means, said fastening means providing a structure arranged entirely within the groove, exerting only a lateral stress upon, and removably engaging the rack, and being freely removable from the groove independently with respect to the rack through the top of the groove and while the rack remains intact in the groove.
19. A printing plate base having a groove therein, a separate rack set into the wall of and supported a substantial distance above the bottom of the groove, and means for removably securing the rack in position, said rack being supported independently of said securing means, and said securing means being removable through the top of the groove while the rack remains intact in the groove.
20. A printing plate base having a groove therein, a separate rack set into the wall of said groove, and a normally distended fastening element adapted to be contracted for insertion into the groove, said fastening element expanding in the groove and engaging the rack.
21. A printing plate base having a groove therein, a separate rack set into the wall of said groove, a normally distended fastening element adapted to be contracted for insertion into the groove, said fastening element expanding in the groove and engaging the rack, and means for maintaining said element against movement lengthwise of the groove.
22. A printing plate base having a groove therein, a separate rack set into the wall of said groove, a normally distended fastening element adapted to be contracted for insertion into the groove, said fastening element expanding in the groove and engaging the rack, and means for yieldingly restraining the fastening means against movement lengthwise of the groove.
23. A printing plate base having a groove therein, rack means within the groove, and a normally expanded clip adapted to be contracted and inserted into and removable from the groove through the top thereof, said clip expanding in the groove to hold the rack means in position.
24. A printing plate base having a groove therein, rack means within the groove, a clip insertable into and removable from the groove through the top thereof, said clip being rotatable within the groove, and said clip expanding in the groove to hold the rack means in position.
25. A printing plate base having a groove
- therein, rack means within the groove, a clip insertable into and removable from the groove through the top thereof, said clip being rotatable within the groove, and said clip expanding in the groove to hold the rack means in position, 5
- 5
26. A printing plate base having a groove therein, a separate rack set into the wall of said groove, and a normally distended fastening element adapted to be contracted for insertion into the groove, said fastening element expanding in the groove and engaging the rack, said rack being supported in the groove independently of said fastening element. 10
27. A printing plate base having a groove therein, rack members within the groove, and normally distended fastening means adapted to be retracted and inserted into and removable from the groove, said fastening means being distended in the groove to hold the rack means in position. 15
28. A printing plate base having a groove therein, a rack member along the side wall of the groove, and distendable means within the groove for removably holding the rack member in position. 20
29. A printing plate supporting element having a groove, rack means within said groove, and resilient means within said groove independent of and adapted to hold the rack means in position, said resilient means being bodily movable in the groove independently of the rack means. 25
30. A printing plate supporting element having a groove, a rack, means removably securing said rack within the groove a substantial distance above the bottom of the groove, said means being bodily movable within the groove and independently of the rack. 30
31. A printing plate base having a groove therein, a rack set into the wall of the groove, and fastening means for removably securing the rack in position, said fastening means providing a structure arranged entirely within the groove, removably engaging the rack, said rack being maintained in operating position in the groove independently of the said securing means. 40
32. A printing plate base having a groove therein, rack members on opposite sides of the groove, and a substantially U shaped member engaging said racks above the bottom thereof for removably securing the racks in position. 50
33. A printing plate base having a groove therein, rack members on opposite sides of the groove, and a substantially U shaped member engaging said racks above the bottom thereof for removably securing the racks in position, said U shaped member being removable through the top of the groove while the rack remains intact in the groove. 55
34. A printing plate base having a groove therein, rack means within the groove, a clip insertable into and removable from the groove through the top thereof, said clip expanding in the groove to hold the rack means in position, 60
- 65
- said rack means being supported in the groove entirely independent of said clip.

W. F. BRÜGMANN.
